(57) **CLAIM**

The ornamental design for a money clip, as shown and described.

DESCRIPTION

FIG. 1 is a perspective front view of a money clip showing my new design. The dashed lines on the money clip represent stitching. The word "logo" shown in dashed-dot lines is not claimed.

FIG. 2 is a front view of the money clip. The dashed lines on the money clip represent stitching. The word "logo" shown in dashed-dot lines is not claimed.

FIG. 3 is a back view of the money clip. The dashed lines on the money clip represent stitching.

FIG. 4 is a side view of the money clip. The left side view and the right side view are identical.

FIG. 5 is a side view of a variation of the money clip. The left side view and the right side view are identical.

FIG. 6 is a top view of the money clip. The dashed lines on the money clip represent stitching.

FIG. 7 is a bottom view of the money clip. The dashed lines on the money clip represent stitching.

FIG. 8 is a perspective front view of the money clip showing a credit card inside the money clip. The card shown in dashed-dot lines is not claimed. The dashed lines on the money clip represent stitching. The word "logo" shown in dashed-dot lines is not claimed.

FIG. 9 is a perspective front view of the money clip with the money clip in an opened position. The dashed lines on the money clip represent stitching. The word "logo" shown in dashed-dot lines is not claimed.

FIG. 10 is a perspective front view of the money clip with the money clip in an opened position and a credit card placed in the money clip. The dashed lines on the money clip represent stitching. The word "logo" and the card shown in dashed-dot lines are not claimed.

FIG. 11 is a perspective front view of the money clip with the money clip in an opened position and a credit card placed in the money clip. The dashed lines on the money clip represent stitching. The word "logo" and the card shown in dashed-dot lines are not claimed.

FIG. 12 is a bottom view of the money clip with the money clip in an opened position; and,

FIG. 13 is a perspective front view of a money clip showing the second embodiment of my new design without a logo. The dashed lines on the money clip represent stitching.

1 Claim, 9 Drawing Sheets
